UNITED STATES PATENT OFFICE.

FRANKLIN H. WOLEVER, OF CHICAGO, ILLINOIS.

MIXING DEVICE TO PRODUCE A COMBUSTIBLE MIXTURE.

Application filed March 6, 1920. Serial No. 363,682.

To all whom it may concern:

Be it known that I, FRANKLIN H. WOLEVER, a citizen of the United States, and a resident of Chicago, in the county of Cook and State of Illinois, have invented certain new and useful Improvements in Mixing Devices to Produce a Combustible Mixture; and I do hereby declare that the following is a full, clear, and exact description thereof, reference being had to the accompanying drawings, and to the characters of reference marked thereon, which form a part of this specification.

This invention relates to a novel automatic mixing device adapted for use for automatically controlling the admixture of the constituents of a burning mixture, as the mixture of air and a natural or artificial gas or vaporized oil, such mixture to be burned for heating to a high temperature mufflers, furnace, boilers, and the like. The device is so arranged that it can be used with a fan blower as a means for propelling through the mixing device free air and air mixed with gas, the gas being automatically controlled by an automatically operated valve, which, in turn, is controlled by partial vacuum and impact pressure action of air flow against the opposite sides of a variable surface perforated element that is arranged in the path of the moving air and surrounded by an orifice 19' between it and the wall of the conduit through which the air flows, said parts being so arranged as to afford and maintain variable impact surfaces on the said element to correctly operate the gas valve to mix the proper proportion of the hydrocarbon element of the fuel with the air.

Among the objects of the invention is to provide an improved mixing device for the purpose set forth, in which the constituents of the mixture, air and gas, may be regulably controlled and in which the proportions of the constituents may be maintained constant for any given regulation of the device to control volume of the mixture.

A further object of the invention is to provide novel means wherein and whereby the gas valve is arranged to be under the control of the moving body of the air constituent of the fuel as it enters the mixing device, the air acting by impact and vacuum against an impact element that controls the

gas valve, so that the moving body of air or fuel constituent, which is ultimately mixed with the gas serves prior to said mixture to control the supply of the gas constituent of the fuel.

A further object of the invention is to provide a novel impact element in a device of this character that is so arranged as to vary the opening pull on the gas valve by varying its surface against which the air impacts.

Another object of the invention is to provide a novel means of varying the effective force of the pressure of the moving column of air on the impact element, which consists in forming the said element with a series of apertures and resultant solid areas, and providing means for varying the area of said apertures and thereby the areas of the solid portions of said elements.

Another object of the invention, in respect of the impact control of the gas valve just described, is to provide means for varying the action of force to variably control the opening and closing movement of the gas valve.

A further object of the invention is to provide, in a mechanism of this character, means to positively pull the constituent elements into the device and discharge them therefrom, embracing a fan blower at the exit end of the device.

Other objects of the invention are to further improve and simplify mixing devices for the general purpose set forth and to adapt the same for the specific purpose of use in high temperature mufflers, furnaces, boilers, and the like, and the invention consists in the combination and arrangement of the parts shown in the drawings and described in the specification, and is pointed out in the claims.

In the drawings;

Figure 1 is a partial plan and partial horizontal section of a furnace equipped with a mixing apparatus embodying my invention.

Figure 2 is an axial section of the mixing apparatus.

Figures 3 and 4 are details of the variable surface impact element for controlling the supply of the gas constituent of the fuel to the mixing chamber.

The apparatus shown in the drawings il-

lustrates one embodiment of the invention to disclose the principle of operation thereof, but it is understood that the structural details of the invention may be considerably varied from the disclosed embodiment without departure from the spirit and scope of the claims hereto appended.

Referring now more specifically to the construction of the embodiment illustrated in the drawings; 10 designates what is intended to indicate a furnace for use in the enameling art wherein, the walls 11 of which surround a space in the furnace to receive articles to be heated, and where there is provided between said walls and the outer heavier walls 12 of the furnace a combustion chamber or chambers 13 in which the fuel is burned; said furnace having an exit 14 for the products of combustion and a door opening 15, closed by any suitable form of door.

16 designates as a whole the improved mixing device embodying my invention. It is best shown in Figure 2 in respect of its general construction and as shown in Figure 1 is adapted to the furnace. It is made as follows:

17 designates as a whole a tubular body or casing in which is formed a mixing chamber 18 for the fuel constituents, a controller chamber 19, and an air inlet chamber 20 provided with inlet ports 21 to receive air at normal pressure. Said parts are herein shown as made up of a number of separately formed elements and fixed together as a unitary structure but may, if desired, be made of a single casting.

22 designates the casing of a fan blower, the inlet opening 23 of which coincides with the opening of the chamber 18, the casing being bolted to the blower casing. In the fan blower is located a fan 24 of any suitable form that is fixed to rotate on a shaft 25 that is mounted in an overhanging bearing 26 formed on one wall of the casing. The outlet opening 22' of said fan blower casing communicates with an outlet branch 26^a by which the fuel mixture is conducted to the furnace, as through and by the medium of manifolds 27, 27. In the present instance, the fuel mixture is directed to opposing combustion chambers 13, and two of such manifolds are provided, having outlets 28 that discharge through openings 29 of the enclosing walls 12 of the furnace, suitable tuyers or air mixing devices being, in practice, associated with the outlet ends of the branches 28 and the openings 29 to supply the desired mixture of air to the fuel at the burning points. Valves 30 separately control the flow of the fuel mixture from the manifolds to the combustion chamber. When arranged as described, the manifolds are connected to the outlet 26^a of the blower 22 by means of branches 32, 32.

At the end of the mixing casing remote from the fan blower is a casing 35 in which is formed a gas chamber 36. Exterior to said casing 35 is another casing 37 to form a receiving chamber 38 for gas that is delivered from a suitable source of supply through an automatic regulating valve designated as a whole by 39, with a valve 40 between it and the receiving chamber 38. The construction and operation of the automatic valve 39 is such that gas under constant pressure can be supplied to the chamber 38, the valve 40 being designed to more or less throttle the flow of gas to the receiving chamber 38.

Between said chambers 38 and 36 is a port 40^a which is controlled by a valve 41, in the nature of a poppet valve, the valve having an annular tapered face to engage a tapered seat around said port. Said valve is provided with a stem 42 which extends through a guide 43 of the carburetor casing and into the controller chamber 19. Fitted to said valve stem in said controller chamber are a pair of discs 45, axially pierced by said stem and confined thereon by nuts 46, the end of the stem being threaded to receive said nuts. Said threaded end of the stem is also guided by a guide bar 48. The said controller chamber 19 is herein shown as cylindric and the discs 45 are also cylindric and are made of such diameter as to less than fill the cross section of the controller chamber 19, thus providing the annular orifice 19' of constant area for air flow. Said discs are provided with a plurality of openings 50 (Figure 4) which are adapted, by relative rotation of the discs, to be brought into and out of register, as indicated in Figure 4, so that the discs when thus associated and fastened to the stem 42 by the nuts 46 constitute a variable surface impact element for a purpose herein described. It may be said at this point, however, that when the openings 50 are fully in register, the discs present a minimum impact surface facing the air inlet ports 21, the air passing through said openings and through the orifice 19' on its way to the mixing chamber, and when the discs are relatively angularly displaced about their common axis, the impact surface is increased, the maximum impact surface being obtained when the openings are wholly out of register. The ported discs are held in fixed adjusted positions by the nuts 46.

52 designates a gas chamber which surrounds the mixing chamber 18, and is shown as concentric therewith, between the controller chamber 19 and the mixing chamber 18, and its inner wall is provided with a plurality of ports 53, through which communication is had between the gas chamber 52 and the mixing chamber 18. Said gas chamber 52 is connected to the chamber 36

by one or more passages 55 formed in the wall of the casing, or otherwise, said passage being such that gas entering from the chamber 38 through the chamber 36 is free to 5 pass to the chamber 52 when the valve 41 is open and is also free to pass to the mixing chamber.

Fixed or connected to the end of the stem 42 remote from the impact element, as 10 by means of a pivot pin 56 is an adjusting lever 57 that is fulcrumed at 58 to a fixed member 59 of the casing. The said adjusting lever 58 is provided on its outer edge with a series of notches 60 which are adapt- 15 ed to be engaged by a hook 61 that is fixed to one end of a controller spring 62, the other end of which controller spring is connected to a threaded stud 63, that is threaded in an adjusting plug 64 whereby the ten- 20 sion of spring 62 may be varied. The plug fits with a gas tight joint between it and the wall of casing 37. A cap 65 threaded on a tubular flange or boss 66, coaxial with the stud 63, serves to further seal up the stud 25 63 against leakage and also to enclose the stud. Furthermore, the force by which the valve 41 is held against the seat may be further varied by changing the hook 61 of spring 62 from one to another of the notches 30 60 in the lever 57.

Located in the mixing chamber 18 is a 35 damper valve 70, having the form of a butterfly valve. Said valve is adapted to control the volume of the fuel mixture from the chamber into the casing 22 of the fan blower, and it may be operated by an exterior hand lever 71, shown in Figure 2, or by means of a 40 thermostatic control associated with the furnace.

In operation the blower provides the 45 motive power by which the air is drawn through the mixing device and said blower is operated at a constant speed, and the volume of air mixed with the correct amount of gas for perfect combustion is varied by 50 partially closing the butterfly valve 70.

The discs 45 act as a controlling means for the gas that enters through the regular valve 39 thence into chamber 38 with- 55 in which the gas is kept at a constant pressure through the controlling action of the pressure control valve 39.

The discs 45 are provided with a series of 60 closable openings 50 which are used to regulate the amount of air that is passing through these openings, and in combination with the fixed annular orifice 19' limits the flow of air to less than will pass through the outlet of the fan at 22'.

The sum total of the combined areas of 65 openings 21 will be equal or be greater than the area of the blower opening 22'. Therefore, air that is discharging through the outlet 22' will not be retarded by reason of any 70 restriction of areas, whilst the air that is

passing through the series of openings 50 within discs 45 together with the fixed ori- 75 fice 19' around the disc will retard the flow of air to the extent that a slight partial vacuum will exist on the blower side of discs 45, and this will cause the discs 45 to move slightly in the direction of the blower intake, thus opening the valve 41 against the spring tension 62 and allowing the gas at constant pressure to flow around valve 41 75 and through seat 40^a, thence into chamber 36 to chamber 52 and through holes 53, joining the body of air within chamber 18.

The valve 41 is held against the gas pres- 80 sure in chamber 38 through the action of the spring 62, and its adjusting screw 63 may be screwed in or out to lessen or strengthen the spring resistance in 62. Further adjustment may be made by changing the spring action to the varied positions of notches 60, lessening the leverage or increasing the action on fulcrum 58, causing greater or lesser pres- 85 sure of valve 41 against seat 40^a. This adjustment, together with the aperture control in discs 45, will admit a larger range of va- 90 riety to suit the fuel value of gas and its relation to the flow of air through the mix- 95 ing chamber 18 and out through the blower at 22'.

Therefore, it is evident that with a free 95 flowing current of air through the openings 21 and a restricted flow through the discs 45 and through the fixed orifice 19' and into the channel 18, with the position of the but- 100 terfly valve full open, there will exist a partial vacuum on the blower side of discs 45 which will hold the valve 41 away from the seat 40^a and cause enough gas to mix with the air flowing through openings 21 to give a proper mixture at the maximum ca- 105 pacity of the apparatus. Should now the butterfly valve be partially closed, the air current in chamber 18 is partially throttled, causing less air to flow through the open- 110 ings 21 and lessening the partial vacuum on blower side of discs 45, causing it to move backward under the influence of spring ten- 115 sion 62, thus correspondingly throttling the gas supply and keeping the mix constant under a lesser flow through the mixing de- 120 vice and through blower orifice 22' into the furnace.

In addition to the unbalanced atmospheric power acting against the disc 45 there is also an impinging power of air due to ve- 125 locity of air travelling in a changed direc- 130 tion while passing through the orifice 19' and through openings 50 of the discs 45, which also is an aid to the gas regulating formation.

The regulating valve 39 furnishes gas at a constant pressure to the chamber 38, and in starting, this pressure will be low. The fan 24 is now operated, either by a motor 75 on the fan shaft or by a belt drive and

the damper valve 70 is full open, or in the position shown in Figure 2. The gas valve 41 is now opened and an ignition test is made at the blower outlet or in the furnace. 5 If the resultant mixture of gas is lean, the cap 65 is removed and the plug 64 is adjusted so that the tension of the spring 62 is relieved to permit the valve 41 to be opened with a lesser impact pressure. If 10 this adjustment be not sufficient, the hook 61 of spring 62 may be moved towards the fulcrum 58. When the parts are so adjusted the operation of the fan 24 has the effect of drawing the air through the chambers 20, 15 19, and 18, producing a low pressure in chamber 18 in rear of impact element 45, and, by reason of the fact that the impact element is in the path of the moving air, the kinetic energy of the moving body of 20 air plus the pressure due to the partial vacuum in the chamber 18 acts on the face of the impact element and serves to open the valve 41, a portion of the air passing through the openings 50 of the impact element and a portion thereof through the 25 space 19' around said impact element. The air thus set in motion by the fan is in the chamber 18 mixed with the gas constituent of the fuel which is supplied to the chamber 30 52 through the chambers 36 and 52 and the ports 53. If it should be found that a sufficient volume of gas is not thus drawn into the mixing chamber and mixed with the air to produce the desired mixture, or more air 35 is being pulled through the device than desirable to produce a good burning mixture, the discs of the impact element 45 will be released and angularly adjusted so as to increase or decrease the active surface of said 40 impact element and thereby increase or decrease the effective pull, due to the kinetic energy acting on said impact element and the partial vacuum chamber 18 to open the valve 41. 45 By reason of the fact that the pressure within chamber 38 is a constant pressure and by reason of the fact that the valve 41 is under the delicate control of the elements 62, 57, and 45, it will be observed that said 50 elements may be adjusted for an accurate proportioning of the gas to the air to produce a good burning mixture, notwithstanding the total volume of the mixture which is drawn from the carburizer through or 55 by the fan or blower, this total volume being varied by the opening and closing of the valve damper 70.

I claim as my invention:

1. A mixing device provided with an air and a controllable constant pressure gas inlet, a valve to control the latter inlet and a variable surface impact element acted upon by the kinetic energy of air flow to control said valve.
2. A mixing device having separate in-

lets for air and gas, a valve to control the gas inlet and a variable surface element acted upon by the kinetic energy of the flow of air through said air inlet opening to control said valve. 70

3. A carburizer provided with an air and a controllable, constant pressure, gas inlet, a valve to control the latter inlet and an apertured, variable surface impact element acted upon by the kinetic energy of air flow 75 to control said valve.

4. A mixing device having separate inlets for air and gas, a valve to control the gas inlet, a variable surface element acted upon by the kinetic energy of the flow of air through said air inlet opening to control said valve and having means to increase and decrease its area against which the air acts and provided with means to fixedly maintain said element in adjusted positions. 80 85

5. A mixing device having separate inlets for air and gas, a valve to control the gas inlet, a variable surface element acted upon by the kinetic energy of the flow of air through said air inlet opening to control said 90 valve and comprising perforated flatwise engaging discs adapted by relative angular displacement to vary the registration of the perforations of the discs.

6. A mixing device having separate inlets for air and gas, a valve to control the gas inlet, a stem connected to the valve and axially guided and a variable surface impact element connected to said stem in the path of the air flow to said mixing device. 95 100

7. A mixing device having separate inlets for air and gas, a valve to control the gas inlet, a stem connected to the valve and axially guided, two flatwise engaging perforated discs mounted on said stem in the path of the air flow to said carburizer and angularly displaceable to vary the registration of the perforations therein and means on the stem to clamp said discs together. 105

8. A mixing device comprising a mixing chamber provided with an air inlet and therebetween with a controller chamber, a gas inlet for delivering gas to said mixing chamber and provided with a controlling valve, and a variable surface impact element 110 in the controller chamber and connected to said valve to control the open position of the valve. 115

9. A carburizer comprising a mixing chamber provided with an air inlet and therebetween with a controller chamber, a gas inlet for delivering gas to said mixing chamber and provided with a controlling valve, and an apertured, variable surface impact element in the controller chamber 120 and connected to said valve to control the open position of the valve. 125

10. A mixing device comprising a mixing chamber provided with an air inlet and therebetween with a controller chamber, a 130

gas inlet for delivering gas to said mixing chamber and provided with a controlling valve, a variable surface impact element in the controller chamber and connected to 5 said valve to control the open position of the valve, and means to induce flow of air and gas to the mixing chamber.

11. A mixing device comprising a mixing chamber provided with an air inlet and 10 therebetween with a controller chamber, a gas inlet for delivering gas to said mixing chamber and provided with a controlling valve, a variable surface impact element in the controller chamber and connected to 15 said valve to control the open position of the valve, and a volume control valve in said mixing chamber.

12. A mixing device comprising a mixing chamber provided with an air inlet and 20 therebetween with a controller chamber, a gas inlet for delivering gas to said mixing chamber and provided with a controlling valve, a variable surface impact element in the controller chamber and connected to 25 said valve to control the open position of the valve and a fan blower connected to the outlet of said mixing chamber and having a discharge outlet leading to a place of use of the fuel mixture.

13. A mixing device provided with an air and a gas inlet, a valve to control the latter inlet, a variable surface impact element acted upon by the kinetic energy of air flow to control said valve and adjusting 35 means acting on the valve in opposition to the impact element to vary the force required to hold said valve open.

14. A mixing device provided with an air and a gas inlet, a valve to control the latter inlet, a variable surface impact element acted upon by the kinetic energy of air flow to control said valve, a controller member 40 pivotally connected to a fixed part and loosely connected at one end to the valve, 45 and an adjustable yielding element connected to the other end of said pivoted member.

15. A mixing device provided with an air and a gas inlet, a valve to control the latter inlet, a variable surface impact element acted upon by the kinetic energy of air flow to control said valve, a lever pivoted to a fixed support and connected at 50 one end to said valve, a spring connected to the other end of said lever and acting to hold the valve seated and means to adjust the seating force of said spring.

16. A mixing device provided with an air and a gas inlet, a valve to control the latter inlet, a variable surface impact element acted upon by the kinetic energy of air flow to control said valve, a lever pivoted to a 55 fixed support and connected at one end to said valve and provided near its other end with longitudinally spaced notches and a

spring anchored to a fixed part and having a hook element to separately engage said notches.

17. A mixing device provided with an air and a gas inlet, a valve to control the latter 70 inlet, a variable surface impact element acted upon by the kinetic energy of air flow to control said valve, a lever pivoted to a fixed support and connected at one end to said valve and provided near its other end 75 with longitudinally spaced notches and means to vary the seating force of said spring.

18. A mixing device comprising a mixing chamber provided with an air inlet, a 80 gas chamber in which gas is maintained at a constant pressure, a gas distributing chamber surrounding said mixing chamber and communicating therewith, a valve between said receiving and said distributing 85 chambers to control the flow of gas to the latter chamber, and a variable surface impact element between said mixing chamber and its air inlet and connected to and controlling said gas valve. 90

19. A mixing device comprising a mixing chamber, a fan blower connected to the outlet end thereof, an air inlet chamber in communication with said mixing chamber having ports in communication with air at 95 constant pressure, a gas receiving chamber having means to supply gas thereto at constant pressure, a gas distributing chamber surrounding and communicating with said mixing chamber, a conduit connecting the distributing chamber with the gas receiving chamber, a valve to control flow of gas through said conduit, and a variable surface impact element in the path of the air flow from the air inlet to the mixing chamber and connected to and controlling said valve. 100 105

20. A mixing device comprising a mixing chamber provided with an air inlet, a gas 110 chamber in which gas is maintained at a constant pressure, a gas distributing chamber surrounding said mixing chamber and communicating therewith, a valve between said receiving and said distributing chambers to control the flow of gas to the latter chamber, a variable surface impact element between said mixing chamber and its air inlet and connected to and controlling said gas valve, and a volume control valve in said mixing chamber. 115 120

21. In a mixing device for mixing air with a hydrocarbon constituent to produce a burning mixture, a valved gas inlet, and a variable surface impact device in the path of the flow of air to the point of mixture thereof with the hydrocarbon constituent to control said valved gas inlet. 125

22. In a mixing device for mixing air with a hydrocarbon constituent to produce a burning mixture, an air inlet conduit, 130

- a valved gas inlet, and an adjustable impact device movable axially in and smaller in diameter than said conduit and in the path of the flow of air to the point of mixture thereof with the carbon constituent and subject at one side to pressure due to rearward air flow and at its other side to a partial vacuum to control said valved gas inlet.
- 10 23. In a mixing device for mixing air with a hydrocarbon constituent to produce a burning mixture, a valved gas inlet, a variable surface impact device in the path of the flow of air to the point of mixture thereof with the hydrocarbon constituent to control said valved gas inlet, and means acting in opposition to said impact element tending to hold the gas inlet valve closed.

24. In a mixing device, an air conduit, and a blower connected to the outlet end 20 thereof, of a gas pressure control, a valve having means to automatically control it by the kinetic pressure of air acting against an impact element in said conduit connected to said valve, and a damper control in said air conduit to reduce the volume of air and to automatically reduce the kinetic power on the impact element which in turn operates said valve in the proper position 25 to produce the proper mixture of the fuel 30 constituents.

In witness whereof I claim the foregoing as my invention, I hereunto append my signature this 26th day of February, 1920.

FRANKLIN H. WOLEVER.
